(57) CLAIM

The ornamental design for a bracelet accessory concealing a hairband, as shown and described.

DESCRIPTION

FIG. 1 is a front perspective view of the bracelet accessory concealing a hairband according to our design;

FIG. 2 is a rear perspective view of the bracelet accessory concealing a hairband according to our design;

FIG. 3 is a top plan view of the bracelet accessory concealing a hairband according to our design;

FIG. 4 is a bottom plan view of the bracelet accessory concealing a hairband according to our design; and,

FIG. 5 is a perspective view of the bracelet accessory concealing a hairband of FIG. 1, shown in a configuration of use.

The dashed lines shown around the periphery of the bracelet accessory concealing a hairband in FIGS. 1, 2, 4, and 5 represent stitching that is part of the claimed design.

The dashed lines shown around the periphery of the bracelet accessory concealing a hairband in FIGS. 1, 2, 3, 4, and 5, represent stitching that is part of the claimed design. The broken lines in FIG. 5 showing a hand represent environmental subject matter only and form no part of the claimed design.

1 Claim, 3 Drawing Sheets
